UNITED STATES PATENT OFFICE.

HEINRICH HARTMANN, OF AHRENSBÖCK, GERMANY, ASSIGNOR TO FIRM GLOBUS, GUMMI- & ASBESTWERKE G. M. B. H., OF AHRENSBÖCK, GERMANY.

JAR-CLOSURE.

1,178,517.

Specification of Letters Patent.

Patented Apr. 11, 1916.

Application filed June 17, 1915. Serial No. 34,761.

To all whom it may concern:

Be it known that I, HEINRICH HARTMANN, subject of the German Emperor, residing at Ahrensböck, Germany, have invented 5 certain new and useful Improvements in Jar-Closures, of which the following is a specification, reference being had therein to the accompanying drawing.

This invention relates to certain new and 10 useful improvements in closures for preserve glasses and the like and it has for its objects among others to provide a simple and cheap improved form of closure by which the contents of the glass will be preserved for an indefinite period, yet permitting of ready removal of the cap or lid of the glass.

Other objects and advantages of the invention will hereinafter appear and the 20 novel features thereof will be particularly pointed out in the appended claim.

The invention is clearly illustrated in the accompanying drawings, which, with the numerals of reference marked thereon, form 25 a part of this specification, and in which:—

Figure 1 is a side elevation with portions broken away, showing my improved construction. Fig. 2 is a top plan of the glass or jar after it has been sealed.

30 Like letters of reference indicate like parts in the different views.

Referring to the drawings, A designates the glass, jar or other vessel, and B the lid or cover thereof, of any suitable material, 35 such as glass or other analogous substance. The lid is provided with a vertical opening C, preferably disposed centrally thereof, as shown, and the depending outer rim of this lid is supported upon a flat and acid resisting 40 jug-ring D, preferably of inelastic rubber.

This jug-ring is supported on the upper edge of the surrounding wall of the vessel A, as seen in Fig. 1, and the lid rests thereon. A piece or plate E of suitable material, such as in- 45 elastic rubber, is placed on the upper face of the lid B over the opening C, as seen in Fig. 1. A bow F is then placed in position with its ends engaging beneath the flange of the top of the vessel, as seen in Fig. 1, 50 the spring F carried by said bow resting upon the plate E and the other spring of

the bow bearing downward upon the first-named spring, all as clearly indicated in Fig. 1. This serves to hold the plate E fixedly in position over the hole C. The 55 vessel is then sterilized, whereupon the plate E presses itself tightly into the opening and at the same time joins closely the upper surface of the lid. The bow F is then removed. The depending flange of the rim 60 of the lid embeds itself in the jug-ring D and thus a liquid and air-tight joint is formed.

When it is desired to open the vessel, the plate E can be removed by a suitable instrument or it may be penetrated so that the air can enter the vessel, when the lid can be removed.

In order to make the plate E more capable of resisting exterior influence, the upper 70 surface can be covered with linen or other suitable fabric or material.

The inelastic rubber is a composition of unvulcanized rubber mixed with asbestos fibers and rosin. This forms a soft sub- 75 stance which resists acids; it forms an excellent air-tight ring and the composition is exceedingly brittle and thus avoids a future use of the ring.

What is claimed as new is:—

80 A closure for a preserve glass or the like, comprising a lid having a vertical opening therethrough, an inner depending flange to extend within the glass, and an outer depending rim, an inelastic rubber ring adapt- 85 ed to rest upon the upper edge of the glass and be engaged by said rim, a plate of in- elastic material resting on the lid over said opening, a bow having ends to engage be- 90 neath a flange on the top of the glass, a bow spring carried by said bow and resting upon said plate, and an oppositely disposed bow spring carried by said bow and bearing upon the lateral extension of the first-named spring. 95

In testimony whereof I affix my signature in the presence of two witnesses.

HEINRICH HARTMANN.
